Patented Feb. 8, 1927.

UNITED STATES PATENT OFFICE.

ALOIS R. GEISLER, OF SPOKANE, WASHINGTON.

CIGAR.

Application filed February 10, 1926. Serial No. 87,263.

My present invention relates to improvements in cigars and particularly to the butt end of the cigar, which by the utilization of the device of my invention, is provided with a mouth piece for strengthening or reinforcing the cigar whereby the cigar may be preserved in its original formation for the convenience and comfort of the smoker during the smoking period. The mouth piece and its attaching cap are incorporated in the cigar during its process of manufacture and encased in such manner by the cigar-wrapper at the butt end of the cigar as to be invisible and not alter the usual appearance of the cigar. Means are provided within the attaching cap of the mouth piece for filtering and absorbing the nicotine arising as the cigar is consumed, and the device of my invention is capable of being manufactured at sufficiently low cost to permit it being thrown away when the smoked cigar is discarded.

The invention consists in certain novel combinations and arrangements of parts of the device and in its combination with the cigar as will hereinafter be more fully pointed out and claimed.

In the accompanying drawings I have illustrated one complete example and a modified form thereof wherein the parts are combined and arranged according to the best modes I have thus far devised for the practical application of the principles of my invention.

Figure 1 is a view of a cigar with which the device of my invention is embodied with parts illustrated in dotted lines.

Figure 2 is an enlarged detail sectional view at the butt-end of the cigar.

Figure 3 is a detail exterior view of the cap and integral mouthpiece.

Figure 4 is a sectional view at the butt end of the cigar showing a modified form of the invention.

Figure 5 is an exterior view of the device of Figure 4.

In order that the general relation of parts may readily be understood I have illustrated the standard form of cigar 1 with the usual wrapper 2 and filler indicated at 3. The device of my invention forming an attachment for the cigar comprises a cap or cup 4 shaped to conform to the contour of the butt end of the cigar and fashioned with an integral mouth piece 5 which is of the proper shape for retaining the cigar between the

teeth or between the lips of the smoker. The cap and mouth piece are fashioned in suitable manner from any desirable material adapted for the purpose and the integral member is applied to the butt end of the cigar during the process of manufacture to enclose the filler portion of the cigar at that end. The enlarged free edge of the cap is fashioned with longitudinally extending tongues or prongs 6 which render that portion of the cap more flexible and permit it to be closely applied to the outer face of the cigar when the wrapper 2 is rolled around its exterior. The wrapper, as seen in Figures 1 and 2, encircles the cap and mouth piece in the usual spiral formation provided therefor, and as seen in Figure 1 the cigar with the mouth piece and cap incorporated therein presents the usual appearance possessed by standard types of cigars. To insure a more rigid attachment of the cap to the body or filler of the cigar, the tongues or prongs 6 are corrugated transversely as indicated at 7 in Figure 2. Thus as the spirally arranged wrapper is applied to the cap and laid thereon by rolling the cigar, the corrugated prongs are pressed into the body or filler of the cigar with sufficient friction to retain the device in the wrapper and on the body of the cigar.

Preferably the tip end of the filler is cut off square as indicated in Figure 2, and a chamber 8 is thus formed within the cap adjacent to the tubular mouthpiece 5 in which chamber absorbent material, such as cotton or other fibrous material, is located, as indicated at 9 in Figure 2 for the purpose of filtering or absorbing the nicotine and preventing its passage through the tubular mouthpiece.

In the modified form of the invention disclosed in Figures 4 and 5 the cap 10 and tubular mouthpiece 11 are used with the prongs 12 on the cap, but instead of using the chamber 8 as in the previously described form of the invention, a tube 13 which may be of paper or other suitable material is affixed in the mouth piece and extends longitudinally and centrally through the cap. The tube is preferably longer than the cap and is perforated as at 14 for passage of smoke from the body of the cigar through the tube and mouth piece. A filtering or absorbent medium 15, as cotton, may also be used in the tube 13 as shown in Figure 4.

It will be understood that material of

which the tube 13 is composed may be of absorbent material permitting the use of the material 15 to be dispensed with.

In each instance the butt end of the cigar is sealed by the use of the cap and wrapper against passage of smoke through the cigar except through the tubular mouthpiece 5 or 11, and in its passage the nicotine is intercepted and absorbed before it can reach the mouth of the smoker. After the cigar has been consumed, the butt end (with its attached cap and mouth piece) is thrown away as usual.

Having thus fully described my invention what I claim as new and desire to secure by Letters Patent is—

1. A mouthpiece for cigars including a body portion shaped to embrace one end of a cigar filler, a tubular member embedded

in the filler and supported by the body portion, said tubular member having openings 20 to allow smoke to pass therethrough, and said tubular member being formed of absorbent material.

2. A mouthpiece for cigars including a body portion shaped to embrace one end of a cigar filler, an elongated tubular member 25 extended from the central portion of the body portion, the free end of the tubular member terminating at a point beyond the 30 inner end of the body portion, said tubular member being constructed of absorbent material and having openings to permit smoke to pass therethrough, and said body portion having fingers adapted to embrace one end 35 of the filler of the cigar.

In testimony whereof I affix my signature.

ALOIS R. GEISLER.
